UNITED STATES PATENT OFFICE.

WALTER S. ADAMS, OF PHILADELPHIA, PENNSYLVANIA, ASSIGNOR TO
JOHN A. BRILL, OF SAME PLACE.

DESIGN FOR A TRUCK SIDE BAR.

SPECIFICATION forming part of Design No. 23,088, dated February 27, 1894.

Application filed November 28, 1893. Serial No. 492,302. Term of patent 14 years.

To all whom it may concern:

Be it known that I, WALTER S. ADAMS, a citizen of the United States, residing at Philadelphia, in the county of Philadelphia and State of Pennsylvania, have invented and produced a new and original Design for Truck Side Bars, of which the following is a specification, reference being had to the accompanying drawings, forming part thereof.

This invention has reference to the design of a truck side bar, and its leading feature consists in the peculiar configuration and general appearance of the side bars of the frame and its several parts.

In the drawings Figure 1 is a side elevation of the side bar; Fig. 2, a plan view; Fig. 3, a left hand end view; Fig. 4, a cross section on the line $z-z$ in Fig. 1, and Fig. 5, a cross section on the line $y-y$ in Fig. 1.

1 is the main web of the side bar, which is connected at its ends to axle box yokes 2, 3 which are substantially in inverted U form. The yoke 2 lies above the plane of the lower edge of the main web 1, and the part 3^a of the yoke 2 that joins the web 1 extends to about the longitudinal center of the web 1, where it ends in the form of a shoulder 4. On opposite sides of the top bar 5 of the yoke 2 are projections 6, and from the part 3^a of

the yoke 2 projects a bar 7 that lies parallel with the web 1 and above the latter. The sides of the projection 7 are in curved form, two curves 8, 9 meeting a smaller curve 10 lying between them. The projection 7 also has two openings 7^a. The end of the bar 7 is also curved or rounded at 11. From the part 12 of the yoke extends an arm 13 that is in I form, and said arm is above the lower end of the part 12 of the yoke 2. The yoke 3 extends both above and below the web 1, and the cross bar 14 of said yoke has side lugs 15. From the part 16 of the yoke 3 extends an arm 17 that is in I form and lies on the same plane as the main web 1. The parts 5 and 14 of the yokes 2, 3, respectively are wider than the main web 1 and arms 13 and 17, and the projection 7 is wider than the yoke 2.

I claim—

The design for a truck side bar, substantially as herein shown and described.

Signed at Philadelphia, in the county of Philadelphia and State of Pennsylvania, this 30th day of October, 1893.

WALTER S. ADAMS.
